ATTORNEYS.

UNITED STATES PATENT OFFICE.

JOHN H. VOGT, OF READING, PENNSYLVANIA, ASSIGNOR TO THE NOLDE AND HORST COMPANY, OF READING, PENNSYLVANIA, A CORPORATION OF PENNSYLVANIA.

METHOD OF MAKING STOCKINGS.

Application filed June 5, 1926. Serial No. 113,864.

The main object of my invention is to produce an improved stocking satisfactorily combining the economic and other advantages of circular knitting, with the better forming of the foot inherent in the slower fashioning method of straight or flat knitting. To this end I provide for utilizing the cheaper and quicker circular-knitting machine and method in the production of the leg and of separated front and rear extensions thereof adapted to form respectively foot-top and heel portions of a completed stocking or sock; and for employing the fashioning flat-knitting machine and method in knitting onto such circular machine product a U-shaped foot-bottom-and-toe portion the parallel foot-bottom parts of which are subsequently seamed together and to the foot-top leg extension; thereby providing a satisfactorily fashioned tubular foot, the top of which has been produced on the circular machine and may readily embody such ornamental figuring or striping as is employed upon the leg.

Fig. 1 shows the circularly knitted product with the extensions parted as required for effecting the knitting thereonto of the flat-knitted foot portion.

Fig. 2 shows the circularly-knitted leg with foot-top and heel-tab extensions, as preferably formed.

Fig. 3 shows the leg product illustrated in Fig. 2 with the halves of the parted heel pocket spread as required for the knitting thereonto of the flat-knitted foot-bottom-and-toe; the latter being also shown with its separated foot-bottom halves knitted onto the respective selvaged inner edges of the heel-tab parts, and its connecting toe portion knitted onto the end of the foot-top leg extension.

Fig. 4 shows my completed stocking, the required longitudinal seaming on the foot bottom and sides and on the rear of the leg being indicated.

It has been heretofore proposed that the different processes of circular and flat knitting be both employed in the production of stockings, so as to get the recognized economic benefit of circular knitting where the requirements of satisfactory formation and construction permit, while securing the recognized advantages of flat knitting where most called for; and my present invention consists in the improved method of combin-

ing the circular and flat knitting processes, and the improved product, hereinafter fully set forth; the main characteristic features of the invention being,—first that the top portion of the foot is produced by circular knitting in continuation of and carrying any ornamentation or peculiarities of, the tubularly knitted leg; and second that only the remainder of the tubular foot is flat-knitted, with separated halves of the foot-bottom extending forward from the longitudinal edges of the heel-tab leg extension and seemed to complete the tubular foot.

Fig. 1 indicates a circularly knitted stocking leg 10, having a semi-circular continuation of the front portion thereof to form a foot-top extension 11 and a semi-circularly formed heel-tab extension of the rear part thereof; which latter is formed with selvaged inner edges 12^a and is shown as divided into two parts 12^b, 12^b by a longitudinal cut 12^c at the rear. This cut is shown as extending upwardly into the leg so as to permit of transferring the circularly knitted leg product shown to a flat-knitting machine, for flat-knitting thereonto the foot-bottom-and-toe as shown in Fig. 3.

The circularly knitted leg 10 illustrated in Fig. 1, may be very conveniently produced as indicated in Fig. 2; the semi-circular heel-tab 12 being shown as reciprocatively knitted upon the rear needles only, and knitting of the tubular foot upon all the needles being thereafter resumed as is commonly done after formation of the usual heel pocket. As the lower portion 11^a of the tubular foot shown in Fig. 2 is intended to be cut away on the line *a a a* so as to result in the circular knit product shown in Fig. 1, such lower portion may be made so as to involve as little wastage as is found to be practicable; or reciprocative knitting may be resorted to for producing the essential foot-top extension 11.

Fig. 3 shows the flat-knitted foot-bottom-and-toe portion of the foot, as knitted onto the flattened-out lower portion of the circularly knitted leg; this flat-knit portion being U-shaped, and comprising the spaced-apart foot-bottom parts 15, 15 and the connecting toe portion 15^a.

As clearly illustrated, each of the foot-bottom parts is knitted onto the selvaged longitudinal edge of an outwardly turned heel-tab part 12^b, and continued as a for-

wardly extending strip to the length of the free foot-top leg extension 11, when the connecting toe portion continuation 15^a is knitted onto the end of said foot-top extension. The forming of the toe and fashioning of the foot-bottom parts 15, 15, are of course effected as is usual in flat knitting, but with separate carriers serving the needles for the two parts and a single carrier serving for the toe. Completion of the fashioned tubular foot with its circularly knitted top, requires only the seaming together of the outer edges of the foot-bottom parts 15, 15 along the bottom of the foot as indicated at 20, and the seaming of their respective inner edges to the side edges of the foot top extension 11 along the sides of the foot as indicated at 21; the bottom seam 20 of course being continued through the shaped heel into the leg of the stocking.

It will be readily seen that my invention provides for the economical manufacture of a stocking having a foot embodying all the advantages of the more expensive full-fashioned stocking, and moreover provides for uniformly continuing in the top of the foot absolutely the same texture as in the leg, with identical ornamentation often practicable only in circular knitting, and without danger of the objectionable transfer line

which almost invariably and inevitably shows in the more expensive products.

What I claim is:

The improved method of manufacturing knitted stockings which comprises: knitting 35 a tubular leg-portion; suspending circular knitting and forming on the rear of said leg-portion by reciprocal knitting a selvaged-edge heel-tab portion; resuming circular knitting to form a tubular foot portion 40 extension of said leg and heel-tab portions; cutting away the rear half of said tubular foot portion and longitudinally dividing said heel tab portion to form an integral 45 instep and separate heel-tab extensions of 45 said tubular leg portion, each heel-tab portion having a selvage edge; laterally spreading said heel-tab extensions and flat-knitting to their selvaged edges separate foot-bottom halves; flat-knitting a toe-pocket portion to 50 the ends of said foot-bottom halves and the end of said instep extension; seaming the inner edges of said foot-bottom halves to the side edges of said instep extension; and uniting the outer edges of said toe-pocket, foot-bottom halves, and divided heel-tabs by a rear seam to complete a tubular foot extension for said tubular leg portion.

In testimony whereof I affix my signature.
JOHN H. VOGT.
